UNITED STATES PATENT OFFICE.

VIRGIL C. CRITES, OF LOS ANGELES, CALIFORNIA, ASSIGNOR TO LEROY BAKER
CHAPMAN, OF OKMULGEE, OKLAHOMA.

TANK.

Application filed August 23, 1921. Serial No. 494,512.

To all whom it may concern:

Be it known that I, VIRGIL C. CRITES, a citizen of the United States, residing at Los Angeles, in the county of Los Angeles and 5 State of California, have invented a new and useful Tank, of which the following is a specification.

This invention relates to a metal tank, one of its objects being to provide a tank 10 made out of rolled sheet metal, formed of sections and assembled in a simple and efficient manner whereby the use of grooves, beads, and lugs is eliminated and the cost of the tank materially reduced.

15 Another object is to provide a tank having simple means for sealing the joints, the number of bolt holes being reduced to the minimum in the plates forming the walls of the tank.

20 With the foregoing and other objects in view which will appear as the description proceeds, the invention resides in the combination and arrangement of parts and in the details of construction hereinafter described and claimed, it being understood that, within the scope of what is claimed, changes in the precise embodiment of the 25 invention shown can be made without departing from the spirit of the invention.

30 In the accompanying drawings the preferred form of the invention has been shown.

In said drawings—

Figure 1 is a transverse section through a tank embodying the present improvements.

35 Figure 2 is an enlarged section on line 2—2, Figure 1.

Figure 3 is an elevation of a portion of one of the joints of the tank, more especially the structure shown in Figure 2.

40 Figure 4 is a section on line 4—4, Figure 2.

Referring to the figures by characters of reference 1 designates the bottom of the 45 tank which can be formed of galvanized sheet iron or the like and can be circular in form or can be made up of two or more segments. Bearing inwardly against the margin of this bottom is a series of segmental hoop sections 2 placed end to end and each of which is L-shaped in cross section so that the base 3 of the section will extend under the bottom 1 while the 50 upstanding flange 4 will project upwardly above the bottom. Each of the flanges 3

may be provided at its center with an inwardly extending ear 5 while another ear 6 may be extended upwardly from the center of each flange 4. When the hoop sections 2 are assembled end to end they will 55 fit snugly around the bottom 1. A ring 7 formed of segmental sections is fitted on the bottom and is adapted to abut at its outer edge against the inner surface of the wall 8 of the tank. This wall is made up of 60 galvanized sheet iron plates or any other suitable material which when set up on end will form a cylindrical tank with the edges of the plates 8 spaced apart and bearing against the inner surfaces of the flanges 4. 65 A segmental ring 9 is fitted against the inner surfaces of the sections of the wall 8 and bears downwardly on the ring 7, it being understood that the joints in the ring 7 are placed between the ends of the sections of 70 the hoop 2 while the ends of the sections of the segmental ring 9 are likewise placed between the ends of the hoop sections. Thus lapped joints will be provided between the parts and by extending bolts 10 through 75 the flanges 4, wall sections 8 and ring 9 and by extending additional bolts 11 through the bases 3, bottom 1 and ring 7 the parts may be held together securely. Cleats 12 are mounted on the outer sides of the wall sections 8 so as to cover the spaces between the plates, these cleats being mounted on the 80 ears 6. Additional cleats 13 are arranged on the inner faces of the plates 8 so as to bridge across the spaces between the plates 90 and rest at their lower ends on the ring 9. Bolts 14 are extended through the spaces between the plates 8 and through the cleats. Gasket strips 15 of rubber or any other suitable material are interposed between the 95 cleats 12 and 13 and the plates 8 and by tightening the bolts the cleats will be drawn toward each other so as to compress the gasket strips upon the plates 8 and produce sealed joints. The gasket strips 15 can also 100 be extended along the edges of those portions of the plates 8 between the flanges 4 and the ring sections 9. The bottom can be reinforced by a diametrically arranged metal cleat 16 interposed between and abutting 105 against opposed portions of the ring 7 and another cleat 17 can be mounted on the lower surface of the bottom with its ends abutting against the ears 5. Bolts 18 can 110 then be extended through these cleats and the

bottom and tightened or, if the bottom is made up of two segments the bolts can be extended between the segments as will be obvious.

It will be noted that all of the joints are lapped joints and that the ends of the cleats of every pair terminate at points remote from each other so that lapped joints are produced and there is no danger of leakage. For example the cleat 12 is supported on the ear 6 while the cleat 13 extends back of and is secured to the ear 6. The same arrangement is followed with reference to the cleats 16 and 17. Packing strips 19 can be interposed between the base 3 and the ring 7 so as to engage opposite faces of the bottom 1 and similar packing strips 20 can also be interposed between the plates 8 and the flange 4 and ring 9 respectively.

It will be understood that by constructing a tank as herein described the boring of holes in the parts is reduced to the minimum with a corresponding reduction in the cost of the tank. Furthermore it becomes unnecessary to provide grooves and lugs. The tank can be readily set up without requiring the services of a skilled mechanic.

What is claimed is:—

1. A sheet metal tank including a bottom, a sectional ring secured to the lower surface of the bottom and having upstanding flanges at the outer edges of the sections abutting against the bottom, a flat sectional ring bearing on the bottom, wall plates standing on the bottom and interposed between the flanges and the margin of the flat ring, a sectional ring bearing on the flat ring and against the inner surface of the wall plates, and means extending through the rings and plates for binding them together, each section of each ring lapping the joint between the sections of the opposed ring.

2. A metal tank comprising arcuate wall plates spaced apart at their edges, a sectional ring comprising a base and a marginal flange, said sections being arcuate, a bot-

tom mounted on the base of the ring, said wall plates being mounted on the bottom and against the inner surface of the flange of the ring, a sectional flat ring mounted on the base and engaging the inner surfaces of the wall plates, a sectional ring bearing on the flat ring and engaging the inner faces of the wall plates, means extending through the rings and plates for binding them together, each section of each ring lapping the ends of the sections of the opposed ring, cleats mounted on the flange and bridging the spaces between the wall plates, cleats mounted on the ring opposite the flange and bridging the spaces between the wall plates, and clamping means extending through the cleats and between the plates to hold said plates gripped between the cleats.

3. In a tank the combination with a ring comprising arcuate sections each having a base and a marginal upstanding flange, of a bottom resting on the bases of the sections, arcuate wall plates spaced apart and resting on the bottom and against the inner faces of the flanges, a sectional flat ring secured on the bottom and to the bases, an upstanding sectional ring mounted on the flat ring and engaging the inner surfaces of the arcuate plates, inner and outer cleats bridging the spaces between the plates and supported by the flanges and upstanding rings respectively with their lower ends at different elevations, packing strips interposed between said cleats and the plates, and clamping means extending through the cleats and between the plates, each of the ring sections lapping the joints between the ends of the sections of the ring cooperating therewith.

In testimony that I claim the foregoing as my own, I have hereto affixed my signature in the presence of two witnesses.

VIRGIL C. CRITES.
